(57) CLAIM

The ornamental design for a mobile fisherman cart, as shown and described.

DESCRIPTION

FIG. 1 is a perspective view from above and to the front of my new design for a mobile fisherman cart.

FIG. 2 is an elevational view of the rear of the cart shown in FIG. 1.

FIG. 3 is a left end elevational view thereof.

FIG. 4 is a right end elevational view thereof.

FIG. 5. is an elevational view of the front of the mobile fisherman cart of my new design.

FIG. 6 is a plan view of the top of the mobile fisherman cart of my new design; and,

FIG. 7 is a bottom plan view thereof.

The broken line elements in FIG. 1 depicting fishing rods and reels are environmental elements, and form no part of the claimed design.
